ARROW FLETCHING JIG

Henry A. Bitzenburger, 8920 Arrington Ave.,
Downey, Calif.

Filed Mar. 19, 1964, Ser. No. 79,091

Term of patent 14 years

(Cl. D54—13)

FIGURE 1 is a side elevational view of an arrow fletching jig showing my new design;

FIGURE 2 is a front elevational view thereof;

FIGURE 3 is a plan view thereof taken in the direction indicated by the reference lines 3-3 in FIGURE 1;

FIGURE 4 is an elevational view taken from the opposite side of FIGURE 1; and

FIGURE 5 is an end view taken in the direction indicated by the reference lines 5-5 in FIGURE 1.

I claim:

The ornamental design for an arrow fletching jig, substantially as shown.
